UNITED STATES PATENT OFFICE

150,140

DESIGN FOR A CASING FOR A WASHING
MACHINE OR THE LIKE

Robert K. Kinoshita, Milwaukee, Wis., assignor
to Appliance Corporation of America, Milwaukee,
Wis., a corporation of Wisconsin

Application June 26, 1946, Serial No. 132,002

Term of patent 14 years

(Cl. D49—1)

To all whom it may concern:

Be it known that I, Robert K. Kinoshita, a citizen of the United States, residing at Milwaukee, county of Milwaukee, State of Wisconsin, have invented a new, original, and ornamental Design for a Casing for a Washing Machine or the like, of which the following is a specification, reference being had to the accompanying drawings, forming a part thereof.

In the drawings:

Fig. 1 is a perspective view of a casing for a washing machine or the like, looking towards the front thereof.

Fig. 2 is a similar view looking towards the rear thereof.

I claim:

The ornamental design for a casing for a washing machine or the like, substantially as shown.

ROBERT K. KINOSHITA.
